UNITED STATES PATENT OFFICE.

GEORGE ANTHONY BOSLER, OF CHICAGO, ILLINOIS.

WEATHER STRIP.

1,409,332.

Specification of Letters Patent. Patented Mar. 14, 1922.

Application filed April 27, 1920. Serial No. 377,057.

To all whom it may concern:

Be it known that I, GEORGE A. BOSLER, a citizen of the United States, residing at Chicago, in the county of Cook, State of Illinois, have invented certain new and useful Improvements in Weather Strips; and I do hereby declare the following to be a full, clear, and exact description of the invention, such as will enable others skilled in the art to which it appertains to make and use the same.

This invention relates to new and useful improvements in weather strips and particularly to weather strips used on the bottom edges of doors.

One object of the invention is to provide novel and improved means whereby when the door is opened to a very small extent, the weather strip will be raised from the sill, thus obviating the usual dragging of the strip on the floor or carpet.

Another object is to provide a novel and improved weather strip which is simple and cheap in construction, and positive and durable in operation.

Other objects and advantages will be apparent from the following description when taken in connection with the accompanying drawing.

30 In the drawing:

Figure 1 is an elevation of the lower portion of a door and door frame, showing the invention applied to the door, and with the door in closed position, and the weather strip in lowered position.

Figure 2 is an elevation of the parts shown in Figure 1, but with the door partly open, and the weather strip in elevated position.

Figure 3 is a vertical sectional view 40 through the door and weather strip, on the line 3-3 of Figure 1.

Figure 4 is a top plan view of the weather strip, the door being shown in section.

The lower edge of the door 10 is rabbeted 45 out, as shown at 11, said rabbeting extending the entire width of the door, and to the height and depth desired. Secured in the rabbet, by means of the screws 12, are the angle plates 13, each having a vertical slot 14 in its outstanding wing, and having a bifurcation 15 in the lower end of said wing. An angle plate 16 is secured in the rabbet, adjacent the outer or free edge of the door. An elongated and flat bar 18 is disposed 50 through the slots of the angle plates 13 and through the outer wing of the plate 16 for

sliding movement, said bar having a pair of obliquely arranged slots 19 formed therethrough, and each arranged adjacent one of the angle plates 13. Disposed for vertical 60 sliding movement in the bifurcations of the angle plates 13, is a pair of elongated flat plates 20, between which is secured a longitudinal strip of rubber 21. Formed integrally on one of the plates 20, at points 65 adjacent the angle plates 13, are the vertical arms 22, and pivotally connected to each of the arms is a link 23. The other end of each link is pivotally connected to the transverse attached portion of an angle 70 plate 13. Carried by each link 23 is an outwardly extending pin 24 which rides in a slot of the bar 18. The outer end of the bar 18 extends beyond the free edge of the door, and encircling the end of the bar, outwardly of the angle plate 16, is a coil spring 75 25, the inner end of which bears against the outstanding portion of the said plate, while the outer end bears against a stop plate or collar 26, secured to the bar. Thus, as the 80 bar is moved toward the hinged edge of the door, the spring will be compressed, and when released, the spring will restore the bar to its normal extended position.

Secured to the face of the door frame, 85 at the free-edge side of the door, is a block 27 having an inclined face for engagement by the projecting outer end of the sliding bar 18, whereby when the door is moved into closed position the bar will be moved longitudinally across the door, in a direction 90 toward the hinged side thereof, with the result that the walls of the slots 19 will engage with the pins 24 causing the downward pivotal movement of the links 23, and 95 the lowering of the weather strip into contact with the sill or threshold of the doorway.

The fact that the end of the bar 18 engages with the member 27 on the portion 100 of the door frame, at the side engaged by the free edge of the door, insures that the weather strip will be automatically elevated from contact with the sill, when the door is moved open to a slight degree. In 105 weather strips of the above-described character, heretofore, the sliding rod bore against the other or hinged side of the door frame, with the result that the door must, necessarily be opened to a point approximately 110 six inches before the weather strip will rise from the sill. In the present device, the dis-

tance of movement of the door, to permit the weather strip to rise from the sill, depends on the width of the inclined face of the inclined block, 27, across which the adjacent end of the bar 18 slides. This, ordinarily, is a matter of an inch, or slightly more. Thus, the weather strip is quickly and properly elevated so that it will not drag on the floor or carpet of the room.

10. What is claimed is:

A weather strip structure including a movable support, in combination with longitudinally aligned slotted brackets carried by the support, links extending longitudinally 15 of the support and each being pivotally con-

nected at one of its ends to a bracket and having an outwardly extending pin, a weather strip member extending longitudinally beneath the links, vertical arms carried by the weather strip member and pivotally connected to the other ends of the links, and a spring pressed bar slidable through the brackets and having oblique slots receiving the pins therethrough.

In testimony whereof, I affix my signature, in the presence of two witnesses.

GEORGE ANTHONY BOSLER.
